ABSTRACT: An improved shuttleless loom produces a woven zipper fastener stringer with a preformed fastener element strip and woven wing sections which extend from the web of the tape over the fastener element strip. The improvement includes a divider bar to keep the warps in the upper wing section separated from those of the lower wing section without the necessity of bulky and special harnesses. The divider bar has a slight up and down movement in unison with a fastener element strip guide which moves the strip alternately above and below the needle path. A further feature of the improved control of the wing warps is a guide which delivers the warps to the fell at a relatively wide angle. The divider bar may also carry a finger for directing the weft thread into proper position around the fastener element strip.

SHUTTLELESS LOOM

This invention relates to shuttleless looms intended for weaving a zipper fastener stringer of the kind shown in my copending application Ser. No. 622,217, filed Mar. 10, 1967 now U.S. Pat. No. 3,454,052. The fastener strip may be of the continuous coil type, or it may take other forms such as independent fastener elements connected together by one or more threads or cords.

As disclosed in the aforesaid application, the complete woven zipper fastener stringer has a fastener element strip extending along one edge of a flat woven web and top and bottom wing sections which are integrally connected to the web and extend over the fastener element strip so as partially to cover the fastener.

One of the principal objects is to control the complex array of warps in the wing sections and the fastener element strip so that the upper wing warps will never interfere with the bottom wing warps. To this end, there is provided a divider which separates the top and bottom wing warps and such divider rises and falls together with the fastener element strip guide to insure proper placing of all warps and fastener strip when the laying needle enters the shed alternately over and under the strip.

Along with this divider bar, the wing warps are further controlled by means of a guide at a convenient point between the heddles and the needle path. The guide is spaced outwardly from the web warps so that the wing warps are delivered to the fell at a substantially wider angle than would be the case if they approached the fell directly from the heddles.

Another object is to provide improved means associated with the warp divider for directing the weft thread as it is being laid by the needle always into proper position between the fastener elements.

With the above-mentioned means for controlling the various warps in the wing sections and the fastener element strip, an improved product can be woven without the addition of bulky cams and harnesses which could not be accommodated in a standard loom. The outward pull of the warps in the wing sections which is effected by the above-mentioned warp guide, ensures a resultant product where the wing sections will stay in place rather than being pulled back around the fastener strip toward the web after the weaving tensions are released.

Other objects and advantages of the invention will hereinafter more fully appear.

In the accompanying drawings, I have shown for purposes of illustration, one embodiment which the invention may assume in practice. In these drawings:

FIG. 1 is a schematic view in plan illustrating portions of my improved loom which are pertinent to the invention;

FIG. 2 is a schematic view in perspective of the same portions seen in plan in FIG. 1;

FIG. 3, 4, 5 and 6 are schematic views in side elevation showing various stages in a complete weaving cycle;

FIGS. 7 and 8 are diagrammatic views in cross section and plan respectively, of a portion of the completed product as made on my improved loom; and

FIGS. 9 and 10 are plan and side elevation views respectively, on an enlarged scale showing the weft control finger and associated parts.

The particular fastener element strip with which I have shown my improved loom has a continuous coil filament 20 surrounding a cord 21. The coil is preformed to the desired shape with head portions 22 adapted to interlock with similar head portions of a mating coil. The fastener stringer is shown in detail in FIGS. 7 and 8 and in the views of the loom the cord 21 is omitted so as to simplify the illustration. The flat part of the tape or web is made up of the usual web warps W and weft or filling thread F. The top wing section contains the top wing warps 1, 2, 3, 4, 5 and 6 while the bottom wing section contains the bottom wing warps 7, 8, 9, 10, 11 and 12, it being noted that warps 5 and 11 are considerably larger than the others in order to build up substantial corners to the structure. Of course, all of these warps are interlaced by the same filling thread F which passes alternately through the top and bottom

wing sections and around the front of the coil between the fastener element heads 22.

In FIGS. 1 and 2, I have indicated only a portion of the web warps W it being understood that these may be shedded in any conventional manner by a group 23 of conventional heddles. Three alternate warps, 1, 3, and 5, in the top wing section will collectively be referred to as Group A and the other three, 2, 4, and 6 as Group B. Those in the bottom wing section will likewise be referred to as Group C and D, Group C including warps 8, 10, and 12; Group D, 7, 9, and 11.

Each of these warps is, of course, shedded by a separate heddle, and some of the heddles may be arranged behind others as indicated in FIG. 1. They are arranged in parallel relation and, of course, suitable means are provided to reciprocate them vertically in the desired timed relation. By reason of the novel features of my loom, the harnesses required for the heddles which handle the wing warps can be arranged alongside those which handle the web warps and need no special actuating means.

The coil 20 is guided alongside the web warps W by means of tubular guide 30 which is located quite close to the fell of the fabric and this guide is moved up and down to position the coil alternately above and below the path of the laying needle N. This needle may be actuated by any known means to move it in a horizontal path so as to lay double picks of weft thread at each change of shed. The means for catching the loops of weft thread and forming a selvage edge as they are projected through the shed may be a conventional knitting needle not shown.

Connected to and extending horizontally outwardly from the fastener element strip guide 30 is a warp divider bar 31 which extends only through the wing warps. This divider bar and coil guide are moved in unison by any suitable means such as a vertical bar 32 connected to a lever 33 which may be pivoted at 34 to a stationary portion of the loom, and reciprocated by any suitable means, a portion of which may be a link 35. Also connected to the lever 33 by a pivot 36 is a bar 37 having a laterally extending fork 38 which engages around the woven stringer immediately after the coil is united to the tape so as actually to shift the coil and the nearby portion of the fell of the fabric up and down all as more clearly shown and described in my copending application Ser. No. 715,076, filed Mar. 21, 1968, now U.S. Pat. No. 3,457,965. Of course, suitable means not shown are provided for guiding the bars 32 and 37 so that the movement of the warp divider 31 and the fork 38 will be substantially vertical.

In order to deliver the wing warps to the fell at a pronounced angle so that the wing sections will remain in place without pulling back by reason of the weft tension, I have provided a comblike warp guide 39 having vertically extending fingers 40 between which pass the upper and lower wing warps. The fingers 40 are long enough so that they retain the warps as they are moved between their upper and lower positions. This comblike guide may be located at a convenient place between the heddles and the needle path, preferably close to the divider bar 31.

As best seen in FIGS. 9 and 10, I have provided a plate or finger 41 which is flexibly connected to the warp divider bar 31. This finger may be of springy sheet material and rigidly joined to the bar 31, or as illustrated, it may have its end 42 bent around the bar 31 so that the finger hinges on the bar. This finger is provided with an enlargement or flanged edge 41a arranged alongside the coil 20 as shown in FIG. 9. This flanged end serves to separate the upper wing warps from the lower wing warps as they are fed into the fell of the fabric. In addition to acting as a further means for separating the upper wing warps from the lower wing warps, this finger has another important function. It extends through the needle path and has a sloping end 43 which is positioned to line up with a space between the fastener element heads 22 so that as the needle N enters a shed the weft thread F will be guided along the sloping end 43 to exactly the right position to fall into the proper space between the fastener elements as the weft thread moves into place around the fastener element strip.

The operation of my improved loom should be evident from the above description. It will be understood that the motions imparted to the divider bar 31 and the fork 38 can be derived from a suitable cam with only one-half the frequency of the needle operation. In other words, the bar 31 and the fork 38 are in the down position for one complete cycle of the laying needle and in the up position for the next cycle of the needle, the timing of the cam being such that the movement between such up and down positions takes place while the needle N is in the withdrawn position. The rise and fall of the fork 38 is only sufficient to keep the coil from being struck by the laying needle N. While there may be a shift of some heddles for the web warps W at each cycle of the laying needle depending on the web pattern desired, the heddles for all wing warps will shift only after every alternate cycle of the needle.

The handling of the warps, Groups A and B for the upper wing section, and Groups C and D for the lower wing section, is depicted at their various positions in FIGS. 3 to 6. The heddles for warps in Groups A and C are designated H1 and those Groups B and D, H2. In FIG. 3, needle N is laying the weft thread F through a shed of the top wing warps, those above the needle path being labeled A and those below B. In this position, part of the bottom wing warps C are in elevated heddles but are prevented from crisscrossing the top wing warp in a region near the coil of the fell of the fabric by means of the divider bar 31.

The shifts successively to the other positions in the cycle can perhaps be best explained by the following diagram of the four different positions where "up" and "down" refer to the positions of the heddles for the wing warp Groups A, B, C, D; the bracketed groups indicating the active shed; and X indicates the group being held out by the divider bar.

I claim:

1. In a shuttleless loom for producing an integrally woven zipper fastener wherein a fastener element strip extends along

one edge of a woven web and integrally woven top and bottom wing sections extend from the web over the fastener element strip so as partially to cover the strip, the warp threads in the woven web being designated web warps and the warp threads

5 in the top and bottom wing sections being designated top and bottom wing warps respectively, the combination of:

a. a weft laying needle movable in a horizontal path for successively laying double picks across said wing sections and web;

10 b. vertically reciprocating heddles for alternately moving all of said warps between upper and lower positions (in the formation and changing of sheds) which are substantially above and below the path of said laying needle where the warps pass through said heddles;

15 c. a warp divider located between said heddles and laying needle, said divider extending through the region of said wing warps only, to maintain all top wing warps always above the divider and all bottom wing warps always below the divider; and

20 d. a guide for said fastener element strip to guide it along side the web warps and at about the same level as said warp divider.

2. The combination defined in claim 1 and means for moving said warp divider and guide in unison between upper and

25 lower positions alternately above and below the level of said needle path.

3. The combination defined in claim 2 wherein said warp divider is rigidly connected to said guide.

4. The combination defined in claim 1 together with warp

30 deflecting means located between said heddles and said needle path and engageable with at least some of said top wing warps and at least some of said bottom wing warps to deflect them laterally outwardly from the web warps whereby they approach the fell above or below the fastener element strip at a substantially wider angle than would be their approach if coming straight from their respective heddles.

35 5. The combination defined in claim 2 together with a finger flexibly connected at one end to said divider and extending between said top wing warps and said bottom wing warps at the level of said fastener element strip to about the fell, the free end of said finger having a sloping outer edge to direct the weft thread being laid by said needle into proper position around said fastener element strip.
